CHARLES BERNASCONI AND RENÉ MARIE BERTHIER, OF CHAMBERY, FRANCE

DESIGN FOR A MAGNETO-ELECTRIC POCKET LAMP

Application filed August 20, 1929, Serial No. 32,469, and in Switzerland April 29, 1929. Term of patent 14 years.

To all whom it may concern:

Be it known that we, CHARLES BERNASCONI, a citizen of the Confederation of Switzerland, and RENÉ MARIE BERTHIER, a citizen of the French Republic, both residing at Chambery, Savoie, France, have invented a new, original, and ornamental Design for Magneto-Electric Pocket Lamps, of which the following is a specification, reference being had to the accompanying drawing, forming part thereof.

Figure 1 is a front view of a magneto-electric pocket lamp showing my new design,

Figure 2 is a rear view of said magneto-electric pocket lamp,

Figure 3 is a top view of said magneto-electric pocket lamp,

Figure 4 is a view of one side of said magneto-electric pocket lamp,

Figure 5 is a view of other side of said magneto-electric pocket lamp.

We claim:

The ornamental design for a magneto-electric pocket lamp, as shown.

RENÉ MARIE BERTHIER.
CHARLES BERNASCONI.
